UNITED STATES PATENT OFFICE.

HERBERT E. WHITE AND THOMAS H. KANE, OF YOUNGSTOWN, OHIO, ASSIGNEES TO THE TRUSCON STEEL COMPANY, OF YOUNGSTOWN, OHIO, A CORPORATION OF MICHIGAN.

MACHINE FOR MAKING WIRE FABRIC.

Application filed May 11, 1922. Serial No. 560,177.

To all whom it may concern:

Be it known that we, HERBERT E. WHITE and THOMAS H. KANE, citizens of the United States, residing at Youngstown, in 5 the county of Mahoning and State of Ohio, have invented certain new and useful Improvements in Machines for Making Wire Fabric, of which the following is a specification.

10 This invention relates to wire working, and more particularly to an improvement in machines for making wire mesh reinforcement of the type used in building concrete roads.

15 To that end the invention contemplates a novel mechanism, and association of instrumentalities, so designed and organized as to provide a practical and reliable machine having means for handling the line 20 wires and the cross wires in a manner to automatically assemble them accurately and uniformly in position to be joined or connected, thereby rendering the machine capable of producing wire mesh of a standard 25 construction, and also in large quantities at sufficient speed for a large commercial output.

A further and more specific object of the 30 invention is to provide a novel stapling or tie-forming unit, for insuring the proper connection between the line wires and the cross wires of the fabric or "mesh". In that connection it is proposed to provide a unit which may be duplicated as desired, 35 and of a construction permitting standardization of parts, at the same time making it possible to utilize any desired number of units in aligned relation to produce a fabric of the desired width. It is, therefore, 40 one of the distinctive features of the invention to provide a stapling or connecting unit for each of the line wires, the same being so designed and equipped as to facilitate the passage of the line wire through 45 the machine, while at the same time assisting in the handling and manipulation of the staple or tie preparatory to its final clinching about the cross wire, thereby connecting the latter to the line wire.

50 The invention also has for its object a

novel consolidation of the tie-forming unit, and the means for making and feeding the cross-wires, whereby the latter in proper cut lengths, and pre-straightened, will be fed singly to position against the line wires 55 at the proper time and in the proper spacing for being fastened to the line wires by the clincher-action of the fabricating unit. In that phase of the invention, the latter also contemplates the employment of 60 a cross-wire making and feeding unit having a large producing capacity and adequate means for feeding the single wires at the desired speeds.

A further object of the invention is to 65 provide a simple and practical arrangement of auxiliary devices for feeding and handling the line and cross wires in proper synchronism with the operation of the stapling units.

70 With the above and other objects in view which will more readily appear as the nature of the invention is better understood, the same consists in the novel construction, combination, and arrangement of parts 75 hereinafter more fully described, illustrated and claimed.

A preferred and practical embodiment of the invention is shown in the accompanying drawings, in which:

80 Figure 1 is a vertical sectional view of the improved instrumentalities for carrying the invention into effect.

Figure 2 is an enlarged vertical sectional view of the machine embodying the fabricating unit for joining or connecting the line and cross wires.

85 Figure 3 is an enlarged detail sectional view of the fabricating unit and the instrumentalities associated therewith for placing a cross wire in position to be connected to the line wires.

90 Figure 4 is an enlarged detail sectional view of the fabricating unit more clearly showing the staple carrier for feeding the staples to the dies of the unit.

95 Figure 5 is an elevation of the staple-plunger die.

100 Figure 6 is a perspective view of the anvil clinching die.

Figure 7 is a detail vertical sectional view taken at right angles to Figure 2.

Figure 8 is a detail view showing the relative position of the staple plunger in its raised position with reference to the staple carrier.

Figure 9 is a view similar to Figure 8 showing the staple carrier pushed back and the plunger lowered.

10 Figure 10 is an enlarged detail elevation of the delivery end of cross-wire supplying unit.

Figure 11 is a perspective view of the fabric or wire mesh.

15 Figure 12 is a side elevation of a multiple unit cross-wire supplying device.

Similar reference numerals designate corresponding parts throughout the several figures of the drawings.

20 In the making of wire fabric or wire "mesh" of the type used in the reinforcement of concrete roads, it is desirable to utilize line wires of relatively heavy gauge to be embedded within the road bed and 25 held in proper spaced relation by a series of transversely disposed cross wires, and it is the purpose of the present invention to provide a machine with adequate facilities for producing a wire mesh fabric of this 30 type in commercial quantities. In that connection it is proposed to provide a novel assembly of devices for handling the wires, and novel means for connecting or joining the same in a thoroughly rigid and practical 35 manner to insure the proper spacing thereof from the time of manufacture until placed in the road bed for use. The type of wire mesh referred to is shown in Figure 11, the same comprising the relatively heavy line 40 wires W and the lighter cross wires W' joined at their intersections by the clinched staples S.

It will be observed from Figure 1 of the drawings, that a machine of the type referred to primarily includes in its organization a novel fabricating unit designated generally by the letter A and which fabricating unit includes those instrumentalities which provide for feeding the line wires and the 45 cross-wires into proper crossing relation, and the means for positioning a staple at the intersection of the line wire and the cross-wire and clinching the same about the two, thereby effecting a fastening or union, at 50 each point of intersection. Also the machine includes in its organization a suitable feeding device B for the line wires, and a cross-wire supplying unit C having means for making and feeding the cross-wires to 55 the fabricating unit in single order at the required intervals. Suitable operating connections are provided between the fabricating unit and the cross-wire unit to effect the 60 operation of these units in unison and proper synchronism thereby to obtain ac-

curacy and reliability in the correlated functions.

Considering first that part of the machine embodying the fabricating unit A, it will be noted that the same includes the particular instrumentalities which function to intermittently assemble the line and cross wires and place the fastening staples thereover whereby the legs of the staples may be finally clinched about the cross-wires to complete 70 the joint. These instrumentalities consist principally of the feeding device B for the line wires, the staple carrier 1, staple plunger die 2, anvil clinching die 3, and the cross-wire carrier 4. The manner in which 75 they are preferably arranged in a machine organization is clearly shown in Figures 1, 2 and 3 of the drawings, and will now be more particularly referred to, the description of the details of each being hereinafter 80 85 more fully set forth.

The upper and lower dies 2 and 3 which have been respectively designated as the staple-plunger die and the anvil-clinching die are carried by the oppositely working 90 jaw members 5 and 6 mounted to reciprocate in the frame F of the machine. The upper jaw 5 may be suspended by the links 7 from the lever arms 8 on the shaft 9; and, as shown in Figure 2, this shaft may also be 95 equipped with the off-set crank arm 10. Said crank arm is disposed at an angle to the arms 8 and is pivotally connected as at 11 with the reciprocatory rod 12 whose lower end is also pivotally connected, as at 13, with the rocker lever 14 located at the bottom of 100 the frame F.

The lever 14 above referred to may be rockably supported as at 15 and preferably carries on one face thereof the spaced oppositely disposed bearing rollers 16 adapted to be engaged by an operating cam 17 on the main actuating shaft 18 suitably journaled in the lower part of the frame. In 105 addition to carrying the operating cam 17, this shaft 18 also carries the eccentrics 19 adapted to receive the bearings 20 of the supporting or connecting rod element 21 which pivotally engages as at 22 with the lower jaw 6. For the purpose of operating 110 the said actuating shaft any suitable and convenient means may be utilized, such for instance as the driving sprocket 23 and chain 24, as shown in Figure 1.

The jaws 5 and 6 which carry the fabricating instrumentalities 2 and 3 heretofore referred to may be of any required length in order to make the desired width of finished fabric, and, for the purpose of 115 properly feeding the line wires W between the jaws to insure accuracy of operation in connecting the line wires and the cross wires a check device D may be employed at the feeding-in side of the fabricating unit A, as shown in Figure 2. This check device 120 125 130

permits the intermittent advance of the line wires upon the forward reciprocating movement of the feeding device B after the same leave the rolls E of the straightening unit 5 G, and prevents backward or retrograde movement of the line wires upon the backward stroke of the feeding device. After passing through the check device D, and issuing from the guide D' thereof the line 10 wires W are delivered into the zone of action of the fabricating unit A which connects the cross wires W' therewith.

In connection with the delivery of the cross wires W' to the fabricating unit from 15 the cross wire supplying unit C, it may be observed that the cross wire carrier 4 previously referred to may be in the form of a shiftable carrier arm 25 having the slotted end portion 26 slidably engaging 20 over the shaft 27 while its opposite end pivotally connects as at 28 with a swinging throw link 29. This throw link 29 is pivotally supported at its lower end 30 on the base part of the machine, thus producing in 25 effect a toggle 25-29 which operates to give the cross wire carrier the necessary upward swinging movement, whereby the cross wire W' resting in the cradle formed by the offset or projection 31 of the arm 25 will be 30 delivered in position above the anvil clinching die 3 so that as the latter rises it will firmly place and hold the cross wire in 35 position against the line wire during the operation of clinching the ends of the staples.

As previously set forth, the fabricating unit A includes the tie forming or clinching means which essentially consists of the staple carrier 1, staple plunger die 2 and 40 the anvil clinching die 3 all of which cooperate to place the staple astride the crossing points of the line and cross wires, automatically, and subsequently effect the complete and secure union between the wires 45 by upsetting the ends of the staple on the anvil die and clinching the same about the cross wires while the bight of the staple embraces the line wire.

Referring first to the structural features 50 and characteristic of the staple carrier 1, it may be observed that the same constitutes a part of a staple magazine (not shown) and serves to deliver the staples in single order to the upper die 2 at proper intervals 55 during the fabricating operation. As will be observed from Figure 4 for example, the said staple carrier may consist of a relatively shiftable and yieldably mounted body or shoe 32 having therein a socket 33 for 60 housing a spring 34 whose tension may be regulated through the medium of the tensioning screw 35 or the like thereby to cause the shoe 32 to be normally pressed forward 65 against the face of the reciprocating staple plunger die 2, and yet permits of the same

being readily forced backward upon the descent of the plunger to insure of one of the staples S being carried downwardly therewith. The upper part of the body of the staple carrier is preferably provided 70 with an inclined carrier bar 36 upon which the staples are hung whereby they may slide downwardly by gravity onto the delivery section 37 which is preferably formed into the curved or arc-shaped formation shown 75 and is of such cross sectional design as to reduce the friction on the traveling staple after it leaves the main part of the bar 36. That is to say, as the delivery section 37 approaches the horizontal plane it is preferable to eliminate as much resistance or friction as possible to permit the free sliding of the staple toward the die 2 so as to insure the proper feed of the staples thereto.

Therefore, as will be observed from 85 Figures 4, 8, and 9, the said delivery section 37 of the carrier bar has its side walls grooved or cut-away to provide in effect the spaced guiding beads 38 at the sides of the section which offer a comparatively small 90 area of contact or engagement for the sides or legs of the staple while the top edge or corners of the rib are also cut-away so as to leave only a single top bead 39, thereby reducing the area of contact between the top 95 of the section and the bight or loop end of the staple. Beneath the extreme end of the part 37 the end of the base of the carrier is provided with the staple clearance notches 40 and the upper corners of the base at 100 each side of the notches is formed with the inclined plunger die engaging shoulders 41 for permitting the free descent of the plunger 2 when the shoulders 42 thereof engage with the carrier and shift it horizontally out of the way.

The inclined die shoulders 42 on the staple plunger die 2, are located on the relatively separate spring legs 43 which are cut away at their lower inner ends to provide 110 a relatively flaring line wire receiving mouth 44 and line wire receiving recess 45, while the face of the plunger, between the shoulders 42 may be formed with a substantially arched recess constituting a staple 115 receiving seat 46. This seat as well as the shoulders 42 may be duplicated on both faces of the die to permit of the reversing thereof when desired.

The upper end of the plunger die 2 may 120 be secured in any suitable and convenient manner to the upper jaw 5 of the machine, and for the purpose of varying the spacing of the legs 43 thereof to regulate the width of the line wire receiving recess 45 and the 125 staple seat 46, and also to compress the legs to grip the staple after it leaves the magazine, the lower ends of the legs 43 pass between the compression heads H of the adjusting or tensioning devices 47 which 130

may be of the nut and screw type shown in Figure 7 of the drawings.

The anvil die 3 which cooperates with the plunger die 2 to clinch the legs of the staples 5 S to the cross wires W' may be carried by the lower jaw 6 in any suitable and convenient manner, as for example, by the clamping bar 48 and the wedge lock 49. As will be seen from the assembly shown in Figure 4 10 the said die preferably fits into a socket 50 formed between the bar and the jaw 6, and the latter, at one side of the die is provided with a plunger clearance recess 51 for permitting the lower end of the stapling plunger 15 to pass by or overlap with the anvil die to complete the clinching operation which is perfected by the head of the anvil die owing to its novel formation which will now be described.

20 By reference to Figure 6 it will be seen that the said head of the anvil die 3 is provided with the main line wire receiving groove 52 and the cross wire receiving groove 53 arranged at right angles to the line wire 25 receiving groove and in a lower plane. At each end of the cross wire receiving groove 53 the die head is formed with the clinching grooves 54 which lie in a plane below the bottom of the groove 53 and receive and 30 direct upwardly the lower ends of the staples S which are preferably bent slightly before being placed in the magazine to insure the curling up thereof about the cross wires as the plunger die and anvil die complete their 35 opposing strokes. The rear edge of the die 3 is also provided with the upwardly inclined face 55 for assisting in the delivery of the cross wire into the groove 53 by the cross wire carrier 4. The arrangement of 40 grooves described in the head of the die 3 is such that the groove 53 for the cross wire permits the same to be carried in a plane below the line wire, but above the plane of the grooves 54 for guiding the legs of the 45 staples into clinched engagement with the cross wire, thereby insuring the up-setting or clinching of the legs of the staples about the cross wires while the web or bight of the cable straddles the line wire.

50 The general operation of the fabricating machine is substantially as follows:—

The main or line wires W which are relatively heavy gauge are fed into the fabricating unit A intermittently by the reciprocating feeding device B, and are prevented from being withdrawn by means of the check device D. This feeding-in of the main or line wires takes place while the jaws 5 and 6 are retracted, and consequently while the 55 stapling plunger 2 is elevated above the anvil die 3. When the stapling plunger 2 is elevated to the proper point the staple receiving seat 46 thereof registers with the end of the section 37 of the staple carrier 60 1 in such a way that the leading staple 65

thereon slides into the seat 46, and then as the stapling plunger 2 begins to move downwardly the shoulders 42 on the plunger engage with the inclined shoulders 41 on the carrier to push the carrier back out of the 70 way, thereby entirely freeing the leading staple from the carrier and carrying it in the seat 46. As the plunger 2 continues to move down, the spring legs 43 are forced together by the compression heads 4 to thus 75 push the staple in the seat 46 and prevent its falling out during the continued downward movement.

In the meantime, when the lower end of the plunger 2 passes the upper end of the 80 die 3 carried by the lower jaw 6 the cross wire carrier 4 delivers one of the cross wires W' over the inclined edge 55 of the die 3, across the top of the groove 52, and into the cross wire receiving groove 53. Because 85 of the overlapped relation of the plunger 2 and the die 3 the cross wire W will be safely positioned in the groove 53, and when the plunger reaches the limit of its downward movement the die 3 will move upwardly toward the line wire and the clinching grooves 54 will bend lower ends of the staples legs about the cross wire W'. Thus when the staple is fully curled about the 90 cross wire W' as shown in Figure 4, the 95 said cross wire is united with the main or line wire W in a thoroughly practical and secure manner. When the joint thus formed is completed the jaws 5 and 6 recede carrying therewith the plunger 2 and anvil die 3, 100 until the plunger die and anvil die reach the limit of their backward strokes, whereupon the anvil die 3 will be ready for the next operation to receive the cross wire W, while the plunger die 2 will permit the staple 105 carrier 1 to slide forwardly again to enable the leading staple on the section 37 to be placed in position to gravitate into the staple receiving seat 46, in the manner already explained. As the staple carrier 1 is adapted to carry an adequate supply of staples on the bar 36 the quantity of staples 110 will always be sufficient to meet the demands of the fabricating operation.

While any suitable and convenient form 115 of machine may be used for making and feeding the cross wires to the fabricating unit, the type of cross wire supplying device C shown in Figures 1 and 10 of the drawings 120 may be conveniently utilized. This device includes in its organization a suitable frame 56 having mounted thereon the wire cutting and straightening device 57. These devices may be of a standard commercial type obtainable on the open market, and no claim thereto is made in the present case, the same being simply illustrated in more or less diagrammatic form and only to illustrate one way of making and straightening 125 the cross wires for delivery onto the in- 130

clined conveyor tables 58 which may consist of a plurality of spaced inclined inverted T-rails or equivalent bars. As will be observed from Figure 1, the said inverted T-bars 5 which constitute the conveyor tables 58 incline toward each other and have arranged therebetween a check and alining partition 59, the same being provided with the alining recesses or grooves 60 in opposite sides there- 10 of and having a segregating gate or head portion 61 projecting into the delivery throat 62 of the magazine chute 63. The described arrangement of the check partition 59 has the advantage of arresting or 15 checking the cut lengths of cross wire at the end of their descent down the inclined feeding tables, and causes the same to straighten or aline with the runway or passage of the delivery chute 63, thereby preventing jam- 20 ming or clogging of the wires at the entrance of the chute and permitting them to be stacked in single order therein, as shown in Figure 10.

From the delivery chute 63 the wires are 25 removed individually by means of a delivery roll 64, the same having a plurality of spaced longitudinal grooves or pockets 65 formed in its circumference for registering at intervals during the cycle of rotation 30 thereof with the end of the delivery chute 63 to receive a single cross wire and carry it through an arc of substantially 180° for deposit on the upper flight of the horizontally disposed conveyor 66. The periphery of 35 the delivery roll 64 has a relatively snug fit with the hood or casing 64a, thereby to insure the cross wires W' remaining in the pockets 65 during the rotation of the roll from the point where it receives the wire, to 40 the point where it discharges onto the conveyor 66, and, to insure that the wires will not shift longitudinally out of the pockets 65 before the proper time for delivery a suitable end guard 67 may be employed. On 45 the other hand, to compel delivery at the proper point a stripper blade 68 may be arranged at such a point that its stripping edge 69 will intersect the circumferential plane of the roll 64 and extend inwardly to a sufficient 50 point as at 70 to reach behind the position occupied by one of the cross wires W' in one of the pockets and forcibly eject the same as it is brought around to discharging position. 55 After the cross wires are deposited in single order on the upper flight of the horizontal conveyor 66, they are advanced to a point where they are picked up by the carrier strip 71 of the upwardly inclining conveyor 72, and this conveyor, in turn, feeds the wires in single order to the delivery conveyor 73 which deposits the cross wires on the cradle projections 31 of the cross wire carrier 4. As will also be observed from 60 Figure 1 the conveyors 66, 72 and 73 may

be driven by the belt or equivalent connection 74 which passes over the pulley 75 of the main driving unit 23 and a pulley 76 on one of the conveyor supporting shafts 77. The delivery roll 64 may also derive its power from the conveyor 66 by the chain or equivalent connection 78.

From the foregoing it will be apparent that the arrangement described provides simple and practical means for maintaining an adequate supply of pre-cut and pre-straightened cross wires for delivery to the fabricating unit A. However, by way of illustrating the range of modification that may be resorted to in the construction of the cross wire supplying unit to obtain increased capacity therefor, reference may be made to Figure 12 of the drawings, wherein it will be observed that the type of cross wire supplying unit C' shown in that figure consists of a battery of cutting and straightening machines 80 arranged at the top of a magazine column 81 having therein a vertical magazine chute 82 which provides materially increased storage capacity for the pre-cut and pre-straightened wires. This magazine chute 82 corresponds in function to the chute 63 in the device C and the wires are individually removed therefrom by the delivery roll 83 which may be provided with the guard and stripper elements 84 and 85 to insure the delivery wires in single order to the horizontal receiving belt or apron 83a. In this form of embodiment the roll 84 may be driven by the gear 86 which meshes with a shiftable clutch pinion 87 slidably carried by an operating shaft 88 and adapted to be thrown into and out of engagement with the gear 86 through the medium of the clutch lever 89. When it is desired to use only one unit, the clutches of all of the remaining units may be opened or thrown out, thereby permitting all except one unit to idle, or on the other hand when an increased capacity is desired all of the clutches 90 may be thrown in thereby causing all of the units to operate and provide an augmented number of cross wires for delivery to the fabricating mechanism.

The operating shaft 88 may carry at one end thereof a driving gear 90 adapted to mesh with a driving pinion 91 actuated by the pulley and belt connection 92-93 from the pulley 94 of the conveyor 83a. This pulley 94 may be driven by belt or chain 95, and the cross wires supplied to the upper flight of the belt 83a may be picked up by the upwardly traveling flight of the conveyor 96 to be fed to the delivery conveyor 73a which performs the same function with respect to the cross wire carrier 4 that the conveyor 73 does in the construction shown in Figure 1.

The multiple unit embodiment of Figure 12, wherein each of the cross wire making

and cutting units is individually controlled enables the operator to meet any requirements as to speed of fabrication, supplying a few, or as many cross wire lengths as the 5 particular operation calls for.

Without further description it is thought that the features and advantages of the present improvement will be readily apparent, and it will of course be understood 10 by those skilled in the art, that changes in the form, proportion, and minor details of construction may be resorted to, without departing from the spirit of the invention, or 15 scope of the appended claims.

15 We claim:—

1. A wire fabricating machine, including an anvil die, having means for positioning angularly disposed wires at their point of intersection and means at one of its sides for 20 looping the legs of a staple, and a staple plunger die that has a portion slideable along said side of the anvil die, said portion of the plunger die having an open side for receiving and holding a tie staple in rear 25 of its end and carrying it to a position to cause it to be looped by the anvil die.

2. A wire fabricating machine including an anvil die and a plunger die relatively 30 movable one alongside the other, the plunger die having an open sided staple receiving seat, and the anvil die having upsetting portions engaged by the legs of a staple carried by the plunger die.

3. A wire fabricating machine including 35 an anvil die and a plunger die relatively movable one alongside the other, the plunger die having an open sided staple-receiving seat, and the anvil die having upsetting portions engaged by the legs of a staple carried by the plunger die, and means for successively delivering staples into the open side of the seat when the anvil die and 40 plunger dies are out of staple upsetting relation.

45 4. In a wire fabricating machine, the combination with relatively movable coacting anvil and staple-carrying dies, of means for delivering staples to the staple-carrying die, and means for causing the staple-carrying 50 die to clamp upon a staple delivered thereto while said staple is caused thereby to be operated on by the anvil die.

55 5. In a wire fabricating machine, the combination with relatively movable coacting anvil and staple-carrying dies, said staple-receiving die having a contractile staple-receiving seat, of means for delivering staples to the seat of the staple-carrying die, and means for contracting said seat to clamp a 60 staple therein while it is being operated on by the anvil die.

65 6. A wire fabricating machine including line and cross wire feeding means, a staple carrier, an anvil die, and a plunger die co-operating with the anvil die and also with

the staple carrier to remove a staple therefrom, said plunger die consisting of spaced legs cut away at the lower inner ends to provide a flaring line wire receiving mouth and a line wire guiding and receiving recess, and also formed in the face thereof at the edges of the line wire receiving recess with a staple receiving seat, and an offset shoulder portion also formed on said legs for engaging with and shifting the staple carrier. 70

7. In a wire fabricating machine, the combination with an anvil die, of a staple-carrying die having spaced legs forming between them a staple receiving seat, means for delivering staples to the seat, means for relatively moving the dies to cause the staple to be upset, and means for moving the legs towards each other upon the relative movement of the dies to clamp a staple 80 in the seat. 85

8. A wire fabricating machine including line and cross wire feeding means, and a fabricating unit including a plunger die and an anvil die mounted to reciprocate toward and from each other, a staple carrier slidably mounted at one side of the plunger die, a spring for maintaining the staple carrier in engagement with the plunger die, and means whereby the latter shifts the staple carrier after stripping a single staple 90 therefrom. 95

9. A wire fabricating machine including line and cross wire feeding means and a fabricating unit including a plunger die and an anvil die mounted to reciprocate toward 100 and from each other, a staple carrier slidably mounted at one side of the plunger die, a spring for maintaining the staple carrier in engagement with the plunger die, and retracting shoulders carried by the plunger 105 for engaging with the staple carrier to shift the same away therefrom after stripping a single staple therefrom.

10. In a wire fabricating machine, the combination with relatively movable coacting staple-carrying and anvil dies, of means for delivering staples to the staple-carrying die comprising a movably mounted body, a guideway for a plurality of staples carried by the body and normally having its delivery end in the path of the staple-carrying die, and means for moving the body and guideway to move the guideway out of the path of the staple-carrying die when the latter is moved. 110

11. In a wire fabricating machine, the combination with relatively movable coacting staple-carrying and anvil dies, of means for delivering staples to the staple-carrying die, comprising a reciprocatory body, a guideway for a plurality of staples carried by the body and normally having its delivery end in the path of the staple-carrying die, a spring operating on the body to move it towards the staple-carrying die, and 125 130

means carried by said die for moving the body and guideway away from it when said die is moved toward the anvil die.

12. A wire fabricating unit including 5 cross-wire feeding means, a staple die and means for removing a single staple from the magazine and placing it over the line wire, a clinching die for the staple, and a cross-wire carrier operatively related to the 10 cross-wire feeding means and comprising a reciprocatory arm having guiding means and provided with a cross-wire holder or cradle to operate and carry the cross-wire into the path of the clinching die.
13. In a wire fabricating machine, a fabricating unit having means for assembling the line and cross-wires, and a cross-wire supplying unit including feeding means for carrying the cross-wires to the fabricating 20 unit, a magazine chute for the pre-cut cross-wires and a delivering device associated with said chute for delivering the wires singly to said feeding means.

14. In a wire fabricating machine, a fabricating unit having means for assembling the line and cross-wires, a cross-wire supplying unit comprising feeding means for carrying the cross-wires to the fabricating unit, a magazine chute for holding and 30 feeding the cross-wires, means for supplying pre-cut cross-wires to the magazine chute, and a delivery device having means for removing single wires from the magazine chute and delivering the same to the 35 feeding means.

15. In a wire fabricating machine, a fabricating unit having means for assembling the line and cross wires, a cross wire supplying unit comprising feeding means for carrying the cross wires to the fabricating unit, a magazine chute for holding and feeding the cross wires, means for supplying pre-cut cross wires to the magazine chute, and a delivery device consisting of a roller 45 having longitudinal wire receiving grooves therein for registering with the magazine chute and adapted to carry the wires therefrom to a point of discharge.

16. In a wire fabricating machine, a fabricating unit having means for assembling the line and cross wires, a cross wire supplying unit comprising feeding means for carrying the cross wires to the fabricating unit, a magazine chute for holding and 55 feeding the cross wires, means for supplying pre-cut cross wires to the magazine chute, and a delivery device consisting of a roller having a plurality of spaced longitudinally disposed wire receiving pockets therein 60 adapted to register at intervals with the end of the magazine chute to receive a single wire therefrom, guard means at the end of the roller for preventing the longitudinal shifting of the wires out of the pockets, and 65 a stripper plate arranged at the discharge

side of the roll and presenting a stripping edge adapted to be engaged by the ends of the cross wires carried by the roller to thereby remove the wires from the pockets.

17. In a wire fabricating machine, a fabricating unit and means for assembling the line and cross wires, a cross wire supplying unit including a magazine chute for the cross wires, a delivery device for the lower end of said chute for delivering single wires 70 to the feeding means, an arresting and guiding partition arranged in line with the magazine chute at the upper end thereof, an inclining table upon opposite sides of the partition for directing the pre-cut cross wires against the same, and wire cutting and straightening machines arranged over and in feeding relation to the inclined tables.

18. In a wire fabricating machine, a fabricating unit having means for assembling the line and cross wires, and a cross wire supplying unit including a magazine chute for the cross wires, a delivery device at the lower end of said chute for delivering individual wires to the feeding means, tables inclining from opposite directions toward the delivery chute, devices for feeding cut and straightened wires to said tables, a checking and guiding partition arranged at the junction of said tables and having a segregating head portion projecting into the entrance of said magazine chute, and said partition being provided with longitudinal grooves at one side of the segregating head for positioning and alining wires for entrance into the delivery chute.

19. A wire fabricating machine including line and cross wire feeding means, a staple magazine, a clinching unit for bending a staple about the line and cross wires, said unit including a plunger die consisting of spaced legs having a staple receiving seat therein, means for compressing said spaced legs to cause the same to grip the staple in the seat after it leaves the magazine, and an anvil die having means for clinching the legs of the staple about the line and cross wires while the staple is held in said seat.

20. A clinching unit for wire fabricating machines including a plunger die having a staple receiving seat, means for feeding a staple into said seat, means for contracting the seat and causing the staple to be gripped by the seat as it descends, and an anvil die having means for engaging and clinching the legs of the staple after the plunger die has completed its movement.

21. In a wire fabricating machine, the combination with an anvil die, of means for feeding line wires across the same, feeding means for moving cross wires successively towards the die, means for transferring the cross wires from said feeding means to the 125

anvil die, and menas for stapling the line and cross wires together at their point of intersection on the anvil die.

22. In a wire fabricating machine, the combination with an anvil die, of means for feeding line wires across the same, means for moving cross wires laterally and depositing them on the anvil die beneath the line wires, and means for stapling the line and cross wires together at their point of intersection on the anvil die.

23. In a wire fabricating machine, the combination with an anvil die, of means for feeding line wires across the same, an endless carrier for moving cross wires successively towards the die, a device that successively transfers the cross wires from the carrier to the die, and means for stapling the line and cross wires together at their point of intersection on the anvil die.

24. In a wire fabricating machine, the combination with an anvil die, of means for feeding line wires across the same, an endless carrier for moving cross wires successively towards the die, an arm having means for

transferring the cross wires successively from the endless carrier to the anvil die beneath the line wires, and a plunger die operating above the line wires for stapling together the line and cross wires at their points of intersection on the anvil die.

25. In a wire fabricating machine, the combination with a fabricating unit and means for assembling the line and cross wires, of a cross wire supplying unit including a magazine body having a chute for the cross-wires, means for delivering cross wires successively from the chute to the assembling means, and an arresting and guiding partition in the chute dividing the same and extending into the body of the magazine.

In testimony whereof we hereunto affix our signatures in the presence of two witnesses.

HERBERT E. WHITE.
THOMAS H. KANE.
